CLAIM

The ornamental design for a display screen or portion thereof with graphical user interface for display of content feedback, as shown and described.

DESCRIPTION

The sole FIGURE is a front view of a display screen or portion thereof with graphical user interface for display of content feedback showing our new design.

The dotted horizontal rule is not claimed. The broken line showing of the display screen or portion thereof and the remainder of the graphical user interface forms no part of the claimed design.

1 Claim, 1 Drawing Sheet

Content Feedback ▼

Distribute content to one or more recipients at the same time. You can decide how many people will review the content and provide feedback.

Name & Instructions
Note your step, add instructions and an optionally add due date for the assignees.

Customer's legal Team Feedback and Review

Instructions
Please review the attached Service Agreement and leave comments with changes or redlines in the document.

Due in (optional)
3 Days

Content
Specify the content that you want feedback on from the assignees.

Service Agreement Other Sales Materials OPTIONAL Assignees
Select a person or group of people that will be providing the feedback.
